UNITED STATES PATENT OFFICE.

LINCOLN A. THORNBURG, OF MUNCIE, INDIANA, ASSIGNOR TO WINDOW GLASS MACHINE COMPANY, OF PITTSBURG, PENNSYLVANIA, A CORPORATION OF NEW JERSEY.

HORSE FOR GLASS CYLINDERS.

No. 916,504.

Specification of Letters Patent. Patented March 30, 1909.

Application filed April 23, 1906. Serial No. 313,194.

To all whom it may concern:

Be it known that I, LINCOLN A. THORNBURG, of Muncie, Delaware county, Indiana, have invented a new and useful Horse for 5 Glass Cylinders, of which the following is a full, clear, and exact description, reference being had to the accompanying drawings, forming part of this specification, in which—

Figure 1 is a side elevation showing a 10 horse constructed in accordance with my invention; and Fig. 2 is an end elevation of the same.

My invention relates to the supporting of glass cylinders for severing into sections, 15 particularly the supporting of long cylinders which are severed into separate flattening lengths or sections.

In the drawings, 2, 2, represent tubular end standards having intermediate tees with 20 a longitudinal connecting brace 3, the upper ends of the standards being connected by the longitudinal member 4. This frame may be built up of gas pipe. The top member 4 is provided with oppositely projecting arms 5, 25 5 having end eyes 6, in which are secured the ends of the cords 7. These cords extend through the eyes 8 of the supporting members proper 9 and then return to the clip members 10. These clip members 10 may 30 consist simply of a wooden block with two holes bored in it, the adjustment being made by sliding the clip along the cord. The supporting members 9 may be curved as shown, and provided with any suitable covering 11 35 of asbestos or any suitable material.

I have shown the supporting members as arranged in pairs to support cylinders on opposite sides of the horse. The horse may, however, be used with a single set of supports if desired. To hold the hanging members against substantial movement, I preferably connect pairs of them by the links 12 having end loops extending around the stems of the members. To prevent swinging 45 toward and from the central longitudinal plane of the horse, I provide links 13 having holes at their inner ends pivoted to the member 3 by bolts 14. The outer ends of these links 13 are engaged with the stems of the 50 supporting members.

In the use of the apparatus, the cords are adjusted by sliding the clips to the proper point, a separate adjustment thus being had

for the series of supports. The glass cylinder is then deposited on the supporting members or rests, which are held against substantial movement, and these members may then be adjusted if desired to give a substantially even support in the different parts of the cylinder which may be of different sizes. The glass may be then cracked off in the ordinary manner, and the severed sections are held by the sets of supports.

The advantages of the invention result from the use of independently adjusted supporting members, which can be adjusted for giving substantially even support throughout the length of the cylinder.

The device is simple, may be cheaply made, and is not liable to get out of order.

Variations may be made in the form and arrangement of the parts without departing from my invention.

I claim:—

1. A horse for glass cylinders comprising 75 a frame having a series of suspended supports, each provided with means for adjusting its height and for preventing it from swinging, substantially as described.

2. A horse for glass cylinders, comprising 80 a frame provided with two series of suspended supports, each provided with means for vertical adjustment and said supports having means to prevent their swinging in either direction, substantially as described. 85

3. A horse having a series of depending adjustable hangers provided with rests for the glass cylinder, and connections for preventing swinging of the hangers; substantially as described.

4. A horse having a double series of adjustable flexible hangers, each having supports for a glass cylinder, and connecting links for preventing substantial swinging of the hangers; substantially as described. 95

5. The combination of a frame, a series of suspended supports on each side of the frame and connecting links between the supports to prevent their swinging.

In testimony whereof, I have hereunto set 100 my hand.

LINCOLN A. THORNBURG.
mark.
